By his Attorney *Alexander Wacewski*

UNITED STATES PATENT OFFICE.

ALEXANDER V. WASCINSKI, OF PASSAIC, NEW JERSEY.

DOUBLE-KEYED VIOLIN.

No. 926,370.

Specification of Letters Patent.

Patented June 29, 1909.

Application filed July 29, 1908. Serial No. 445,882.

To all whom it may concern:

Be it known that I, ALEXANDER V. WASCINSKI, a citizen of the Empire of Germany, residing at Passaic, in the county of Passaic and State of New Jersey, have invented certain new and useful Improvements in Double-Keyed Violins, of which the following is a specification.

This invention relates to violins in which the strings, instead of being strained by pressing the strings by the fingers on the finger-board, are strained by means of keys while the bow is moved over the strings, the improvement being intended for providing double keys, that is to say, keys for the half tones, so as to increase thereby the range of tunes that can be played on the keyed violin; and for this purpose the invention consists in a double-keyed violin or violin-piano, constructed in the manner to be hereinafter described and claimed.

In the accompanying drawing, Figure 1 represents a plan-view of my improved double-keyed violin or violin-piano, Figs. 2 and 3 are vertical longitudinal sections respectively on lines 2, 2 and 3, 3, Fig. 1, showing the strings arranged to be strained by a single key and by a double key, Fig. 4 is a vertical transverse section on line 4, 4, Fig. 3 and Figs. 5 and 6 are perspective views, respectively of the main and auxiliary keys.

Similar letters of reference indicate corresponding parts.

Referring to the drawings, *a* represents the body of my double-keyed violin or violin-piano. The body *a* may be made in any suitable manner, preferably in the form of a lyre, as shown in Fig. 1. The instrument is placed like a zither on a table or other support, and is arranged with a keyboard at the end next to the player. The keyboard is composed of keys *k* and is supported on the front-end of the body, the sounding-board *b* being supported on the end-bars of the frame. Strings *t*, preferably of equal length but of different thickness, are strained over the body of the violin-piano and provided with tuning-pins *t*¹ on the straining-bar at the rear-end of the body *a*, then passed over two straining-pins *t*² arranged in the slotted bodies of the keys *k* and over a glass tube *g* to the hitch-pins *t*³, which are applied to the front-bar of the body, as shown clearly in Fig. 2. The strings pass over a fixed damper *d*, which is supported on end-posts *d*¹ on the body, said damper being provided with a

layer of felt or other damping material *f* on which the strings rest when the keys are in their normal position of rest. The front-ends of the keys *k* when lowered are arrested by a key-rest made of a glass tube *g*¹, which is supported on parallel adjustable bars of a regulator arrangement *e*, said regulating bars being attached at their rear-ends by means of screws *f*¹ to the front-bar of the body *a* and set by means of set-screws *f*² located in front of the fastening-screws higher or lower, so as to raise or lower the key-rest and decrease or increase the stroke imparted to the keys.

The damper-bridge is provided at its ends with upright guide-lugs *d*² for guiding the bow *g*², which is moved over the strings either by the right or left hand, while the keys are operated for playing the music by the fingers of the left or right hand, as desired.

Any number of strings and keys may be arranged, according to the size of the instrument to be made. The strings are tuned to the diatonic scale and so arranged that music within the range of one or more octaves can be played on the instrument. For the purpose of producing a chromatic scale, some of the keys are provided with auxiliary keys *h*, which are located on top of the ordinary keys *k* and provided with straining-pins *t*⁴ over which the string that is strained on the main key is passed, as shown in Fig. 3. In this manner when the main key is depressed the ordinary note is sounded, while when the auxiliary key is depressed an extra strain is imparted to the string and thereby a half tone sounded. The auxiliary keys are slotted at their rear-ends to permit the passage of the strings, and provided with felts *h*¹ at their rear-ends by which they rest on the main keys, while their front-ends are clear of the same. A pointed pin *h*² at one or both of the seats *h*¹ serves for piercing the main key and holding thereby the auxiliary keys in position on the main keys in connection with the straining action of the keys. By the arrangement of the auxiliary keys the range of music that can be played on the improved double-keyed violin or violin-piano is greatly increased and the enjoyment of the instrument enhanced.

The improved double-keyed violin permits the playing of violin pieces without acquiring the difficult art of playing the violin and permits the playing of pieces written for

the violin by amateurs that are not conversant with the playing of the violin.

Having thus described my invention, I claim as new and desire to secure by Letters

5 Patent:

1. A violin-piano comprising a sounding-board, a plurality of strings stretched over said sounding-board, a set of keys to stretch the strings, and a fixed damper extending

10 below the strings provided with means for guiding the bow over the strings.

2. In a violin-piano, the combination, with a plurality of strings, of a set of main keys, and auxiliary keys supported on the main

keys, the strings being stretched over and supported on both main and auxiliary keys.

3. In a violin-piano, the combination, with a sounding-board, and a plurality of strings, of a set of slotted keys having pins in the slots supporting and stretching the strings 2 intermediately of the length of the latter.

In testimony, that I claim the foregoing as my invention, I have signed my name in presence of two subscribing witnesses.

ALEXANDER V. WASCINSKI.
